UNITED STATES PATENT OFFICE.

AMOS C. SMITH, OF ELBERTON, GEORGIA.

HEADBAND ATTACHMENT.

Application filed March 19, 1926. Serial No. 96,070.

My invention relates to headband attachments for earphones such as commonly used for radio or telephone receiving sets and comprises primarily means for regulating the pressure of the earphones against the ears of the user.

An object of my invention is to provide an adjustable connection between the spring-like headband and the earphones by means of which the receiver may be adapted to fit comfortably and securely on persons whose heads are of varying widths as well as of varying lengths. The average earphone set used for radio and similar reception purposes includes a pair of ear engaging devices connected by a resilient headband, the phones usually being adjustable vertically so that the same may be used by persons whose heads vary in length. Heretofore the only means provided for adjusting the phones horizontally so as to adapt the same for persons having heads of varying widths was by bending the headband thereby increasing or decreasing the distance between the phones.

The object of my invention is to provide a novel construction for connecting the headband to the earphones whereby the user may instantly adjust the same to a comfortable position upon his head by moving the same either vertically or horizontally as desired.

With this and other objects and advantages in view I propose the construction and operation of a headband attachment for earphones as more fully hereinafter set forth in the following specification reference being had to the accompanying drawing forming part hereof, wherein like numerals refer to like parts throughout, and in which

Figure 1 is an elevational view of a set of earphones constructed in accordance with my invention,

Figure 2 is a vertical sectional view through the headband connection,

Figure 3 is a perspective view of the regulating thumbscrew,

Figure 4 is a group perspective of the parts forming the gear segment, and

Figure 5 is a view taken substantially along a line 5—5 of Figure 2.

Referring now to the drawings, I have disclosed a preferred embodiment of my invention comprising an arcuate shaped headband 5 formed of a pair of parallelly arranged spring-like wire or other suitable material, and having a padded covering 6 for contact with the top of the head. The ends of the

wire 7 at each side of the headband are curved in opposite directions in the form of a semi-circle, each pair of end sections co-acting to constitute a substantially complete circle and adapted to fit within similarly shaped grooves or recesses 8 formed in the abutting faces of a pair of circular disks arranged in superimposed relation. One of the disks 9 is provided with an upstanding centrally disposed flange 10 and a bore extending therethrough, and the other disk 11 is provided with an enlarged bore through which the flange is inserted, the flange being of sufficient length to extend through and have its outer edge turned down against the disk 11 so as to clinch the parts together. The edge of the disks when in assembled relation is provided with a gear segment 12 arranged at the opposite side from the connection with the ends of the headband.

Arranged for co-acting with the assembled disks, I provide an adjusting screw 13 having a central bore 14 through which is slidably inserted the stem 15 carrying the yoke 16 to which is pivotally mounted the usual type of earphones 17. One end of the screw is provided with a shank 18 of reduced circumference upon which a spirally arranged rib 19 is formed substantially similar in construction to a worm gear which is adapted to mesh with the gear segment 12. An annular flange 20 is formed at the reduced end of the screw and a similar flange 21 is formed thereon intermediate the ends.

A clamp 22 is provided, having a circular head 23 for encircling the worm gear section of the screw and disposed between the annular flanges 20 and 21 and having its ends 24 extended in parallel relation to engage the outer faces of the disks 9 and 11. The ends of the clamp are provided with openings in alignment with the bore of the disks so that a rivet 25 may be inserted therethrough to maintain the clamp and the disks in pivoted relation.

The bore of the screw at the end remote from the end carrying the worm gear is of an increased diameter as indicated at 26, its outer portion being threaded to receive a threaded hollow plug 27. The depth of the increased portion of the bore is sufficient to admit a spiral spring 28 the convolutions of which are arranged to form a sliding tight fit about the stem 15. The spring serves the double function of holding the stem in any set position, thus preventing the

earphones from slipping vertically and also because of the gripping tendency on the stem the rotation thereof is prevented, thus avoiding the twisting of the receiver wires about 5 the earphones.

From the foregoing it will be seen that by providing a gear segment on the disks having their axis at right angles to the screw carrying the worm gear with which the gear 10 segment engages, that the turning of the worm gear will operate to bring the teeth of the gear segment successively into engagement therewith. This operation necessitates the movement of the screw carrying the worm about the axis of the disks, the clamp securing the parts having its ends pivotally carried on the disks to accommodate 15 such movement. The disks being fixedly secured on the ends of the headband 20 cannot turn, therefore limiting any movement to the screw and the parts carried thereby. Thus the movement of the worm through the turning of the screw will result in swinging the stem carrying the earphones 25 from a vertical position to an inclined position and consequently the earphones mounted on the bottom of the stem will be swung horizontally and accordingly into or out of contact with the operator's ears as desired.

30 I claim:

1. A device of the character described comprising a headband, a gear segment formed at one end thereof, an earphone hav-

ing a stem, a hollow screw slidably mounted on said stem, frictional means for maintaining the screw and the stem in adjusted relation, a worm gear formed on said stem and a clamp operatively connecting said gears. 35

2. A device of the character described comprising a headband including a pair of wires, 40 a pair of disks arranged in superimposed relation with the ends of said wires secured therebetween, a gear segment formed on the periphery of said disks, earphones having a stem, a hollow screw slidably mounted thereon, a spiral spring disposed within said screw and frictionally gripping said stem, a worm gear formed on said stem and a clamp operatively connecting said gears. 45

3. A device of the character described comprising a headband including a pair of wires having their ends bent circularly, a pair of disks arranged in superimposed relation, recesses formed on their abutting faces and adapted to receive the ends of said 50 wires, a bore provided in said disks, a gear segment formed on the periphery of said disks, earphones having a stem, a hollow screw mounted on said stem, a worm gear formed thereon, a clamp encircling said 55 screw and having its ends engaging the outer faces of said disks and a pin carried in the bore of said disks and pivotally securing the ends of said clamp thereto.

In testimony whereof I affix my signature.
AMOS C. SMITH.
